US00D611074S

(12) **United States Design Patent**
Bashore et al.

(10) **Patent No.:** **US D611,074 S**
(45) **Date of Patent:** **** Mar. 2, 2010**

(54) **PORTABLE BATTERY POWERED WELDER**

(75) Inventors: **Brian S. Bashore**, Tipp City, OH (US); **Darrell L. Sickels**, Troy, OH (US); **Bernard J. Vogel**, Troy, OH (US); **Caleb R. Krisher**, Appleton, WI (US)

(73) Assignee: **Illinois Tool Works Inc.**, Glenview, IL (US)

(**) Term: **14 Years**

(21) Appl. No.: **29/284,167**

(22) Filed: **Aug. 31, 2007**

(51) **LOC (9) Cl.** **15-09**

(52) **U.S. Cl.** **D15/144**

(58) **Field of Classification Search** **D3/272, D3/273, 276, 279, 281, 282, 295, 905; D15/144, D15/144.1, 144.2; 174/50.56, 50.59; 219/130, 219/131, 132, 133; 290/1 A; 336/182, 195, 336/212, 214; 361/220**

(57) **CLAIM**

The ornamental design for a portable battery powered welder, as shown and described.

DESCRIPTION

FIG. 1 is a perspective view of the design for the portable battery powered welder illustrating a removable door and a detachable cover coupled to a body of the portable battery powered welder, wherein broken lines illustrate environmental features including a carry handle, a pair of hinges and a pair of latches coupling the removable door to the body, a

fastening system coupling the detachable cover to the body, a control panel, a front louver, support ridges, and a wire feed outlet;

FIG. 2 is a front elevational view of the design for the portable battery powered welder as illustrated in FIG. 1;

FIG. 3 is a right side elevational view of the design for the portable battery powered welder as illustrated in FIG. 1;

FIG. 4 is a left side elevational view of the design for the portable battery powered welder as illustrated in FIG. 1, wherein broken lines illustrate environmental features including a rear louver, a power switch, and an electrical plug interface;

FIG. 5 is a top plan view of the design for the portable battery powered welder as illustrated in FIG. 1;

FIG. 6 is a bottom plan view of the design for the portable battery powered welder as illustrated in FIG. 1;

FIG. 7 is a rear elevational view of the design for the portable battery powered welder as illustrated in FIG. 1;

FIG. 8 is a perspective view of the design for the portable battery powered welder as illustrated in FIG. 1, illustrating the removable door rotated away from the body to an open position to reveal an internal compartment having a wire feeder region in the body, wherein broken lines illustrate

environmental features including a wire feeder mechanism and a wire spool mount disposed in the wire feeder region;

FIG. 9 is a front elevational view of the design for the portable battery powered welder as illustrated in FIG. 8;

FIG. 10 is a right side elevational view of the design for the portable battery powered welder as illustrated in FIG. 8;

FIG. 11 is a top plan view of the design for the portable battery powered welder as illustrated in FIG. 8; and,

FIG. 12 is a perspective view of the design for the portable battery powered welder as illustrated in FIGS. 1 and 8, wherein the removable door is removed and not shown for clarity, and the detachable cover is removed from the body to reveal another internal compartment including a battery storage region, and broken lines illustrate environmental features including a first battery and a second battery disposed in the battery storage region.

In these drawings, the solid lines illustrate the claimed ornamental design, whereas the broken lines illustrate environmental features that form no part of the claimed ornamental design.
